Primary Examiner — Antoine D Davis(74) *Attorney, Agent, or Firm* — Niro Law, Ltd.(57) **CLAIM**

The ornamental design for a temperature probe device, as shown and described.

DESCRIPTION

FIG. 1 is a front perspective view of a temperature probe device showing the present invention;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken lines in the figures show structure or boundaries that form no part of the claimed design.
